WATERLESS GASHOLDER

Paul M. Kuehn, Baltimore, Md., assignor, by
mesne assignments, to Koppers Company, a
corporation of Delaware

Application September 9, 1932, Serial No. 632,446
Renewed March 25, 1936

4 Claims. (Cl. 48—174)

This invention pertains to waterless gas holders and more particularly to the sealing means for the piston-like closure employed in conjunction with the holder shell.

The holder of the present invention is of the same general type as that shown in Letters Patent to Jagschitz Number 1,275,696.

The main object of the present invention is to produce a new form of sealing means, the movable sealing elements of which are moved into sealing relation with the shell both by mechanical means and the static head of the sealing liquid maintained in the gutter usually present in holders of the type above specified and located between the piston closure and the movable sealing means.

A further object is to provide a vertical series arrangement of the movable sealing elements and preferably with the statically actuated element intermediate two metallic ones.

The invention is susceptible of modification and several embodiments are herein disclosed.

In the drawings:

Fig. 1 is a vertical sectional view of so much of the shell, piston closure and sealing means as is necessary to an understanding of the invention;

Fig. 2, a perspective view of such parts as are seen from the interior of the shell; and

Fig. 3 and Fig. 4, vertical sectional views illustrative of two modifications.

Referring first to Figs. 1 and 2, 10 denotes the shell of the holder and 11 the piston-like closure therefor.

A gutter for the sealing medium or liquid surrounds the piston, being defined by the vertical wall 12 of the piston, plate 13, and the flexible element 14. This latter extends upwardly and is secured to the lower rubbing bar or element 15 by bolts 16 which pass through said members and a clamping plate 17. The bolts also pass through the upper portion of a spacer member 18 employed to hold the canvas element 14 out of rubbing contact with the wall of the shell as the piston moves relatively to the shell.

Located above the rubbing bar or shoe 15 is a second metallic shoe 19 and the adjacent spaced edges of said members are chamfered or cut away on an arc to produce a seat for a packing and rubbing element 20, preferably of round cross section, which extends through the space between the edges of the shoes and contacts the inner wall of the shell.

A flexible backing and sealing strip 21 bears against the inner portion of the member 20 and

its lower and upper portions are tightly secured to the shoes 15 and 19, respectively, by clamping plates 22 and 23 and bolts designated generally by 24. By this arrangement there is produced a vertically disposed series of rubbing elements, 5 two metallic and an intermediate one formed from any suitable material.

Strip 21, it will be noted, insures the integrity of the outer wall of the gutter and no fluid may pass therefrom other than that which passes 10 downwardly between the shoes and the shell, entering first between the upper bar 19 and the shell.

Strip 21 being formed from flexible material will move outward under the static head of the 15 fluid sealing medium which in practice extends up to the level indicated by the line a, Fig. 1.

The rubbing bar structure is sustained and forced outwardly by a series of weighted levers 25 fulcrumed at 26 on the outer ends of arms 27 20 secured at their inner ends to the wall of the piston. The lower ends of the levers 25 extend downwardly between a pair of bracket members 28 and 29, the levers being fulcrumed at their lower end upon through pins 30 which extend through the brackets, through spacing collars 31, 32, and the lower end of the lever. The upper portions of the brackets are provided with arculate slots through which, and through the lever, passes a pin or rod 33, which construction tends 30 to guide the parts and relieve the pin 30 from undue strain.

The lever construction in and of itself is old. The brackets 28 and 29 are secured to the lower and upper rubbing bars 15 and 19 respectively 35 by bolts which pass through ears 34 and 35 which extend laterally from the brackets.

It will be appreciated, of course, that the weighted levers rocking upon the fulcrums 26 will force the rubbing bar structure outwardly 40 into close contact with the inner wall of the shell,—this being permitted by the flexibility of the gutter element 14. At the same time the lever forces the structure as a whole outwardly into facewise contact with the inner face of the 45 shell, the static head of the sealing medium will, acting through the strip 21, force the packing member outwardly into contact with the shell.

In Fig. 3 a slight modification is shown, the rubbing bars in this instance corresponding to 50 the rubbing bars 15 and 19 of Figs. 1 and 2 being designated by 15^a and 19^a. They are secured to the brackets with which the weighted levers co-operate in a manner as heretofore set forth. The adjacent edges of these bars are separated a 55

distance considerably more than that indicated in Figs. 1 and 2 and instead of employing a round sealing element or shoe a block-like structure 36 is introduced into the space between the adjacent edges of the rubbing shoes or bars. This block may be formed of wood, metal or other suitable material. As under the former construction, a cover sheet 37 of flexible material, such as canvas, bears upon the inner surface of the block and tends to force the same outwardly under the action of static pressure into contact with the inner face of the shell.

In Fig. 4 a further modified form is shown, the metallic rubbing bars in this instance being designated by 15^b and 19^b. As will be seen upon reference to Fig. 4, the adjacent edges or ends of these members are flanged so as to produce a pocket in which is mounted a rubbing block or shoe, as 36^a. This block is provided with an inwardly extending stem 38. A cover strip of canvas or other flexible material 39 is secured to the inner faces of the members 15^b and 19^b and bears against the inner end of the stem or projection 38. A cotter pin 40 may be present in order to facilitate assembly of the parts and to prevent the block from dropping out of place during assembly. As with the other constructions, the strip 39 is subject to static pressure and forces the block 36 outwardly. It also prevents leakage of the sealing medium from the gutter outwardly between the various shoes so that the sealing medium must pass downwardly between the upper shoe 19^b (or 19^a as in Fig. 3) and the inner surface of the shell. In this way a tight seal is effected.

No claim is made herein to the broad combination of a series of rubbing bars or shoes standing in vertical relation and associated with a gutter as that subject matter is claimed in my copending application filed September 9, 1932, Serial Number 632,445.

Reference has heretofore been made to a liquid sealing medium. For this purpose tar, oils, or any material which will form a tight seal between the rubbing bar and the inner face of the shell may be employed.

What is claimed is:

1. In a waterless gas holder, the combination of a shell; a piston-like closure mounted therein; a pair of rubbing bars standing in vertical spaced relation designed to coact with the shell; means for forcing said bars into contact with the shell; a sealing element located between the adjacent edges of said rubbing bars and likewise bearing against the inner surface of the shell; and flexible means lying to the rear of said sealing element and closing off said element from the gutter and acting as a transmitting element to exert the static pressure of the sealing medium within the gutter upon said sealing element to force the same outwardly into contact with the shell. 21

2. A structure as set forth in claim 1, wherein the sealing element has the form of a block against which the flexible means bears.

3. In a waterless gas holder, the combination of a shell; a piston-like closure mounted therein; a gutter for sealing medium extending around said shell; a pair of rubbing bars arranged in vertical relation with reference to each other, with their proximate edges spaced apart and so beveled as to form a space with walls converging toward the shell; a sealing element located within the space thus formed; and means located inwardly of said sealing element and secured to the rubbing bars to prevent ingress of sealing medium to said sealing element. 30

4. A structure as set forth in claim 3, wherein the sealing element is substantially round in cross section.
